SPARK PLUG SETTING

Joseph A. Fink, Englewood, N. J.

Application March 10, 1945; Serial No. 582,068

3 Claims. (Cl. 123—169)

This invention relates to improvements in multi-cylinder internal combustion engines and, more specifically, it relates to a new and improved spark plug setting.

The modern development of internal combustion engines has a tendency toward increasing the number of cylinders which results in an increased number of spark plugs. The spark plugs have to be detached and replaced from time to time for the purpose of cleaning, adjusting, repairing or exchanging the same, or in cold weather it is frequently necessary to remove the plugs for dripping gasoline into the cylinders in order to overcome difficulties in starting the engine. If an engine has six, eight, twelve or more cylinders, the unscrewing and resetting of each single plug is very bothersome and requires much time. Moreover, the cylinderheads which carry the plugs are often made of aluminum or other light metal, so that a considerable amount of skill, care, and experience is necessary for re-screwing the plugs, because if the same are tightened too strongly, the threads of the spark plug holes will wear out and expensive repairs or the buying and installing of a new cylinder-head will be necessary.

It is, therefore, the main object of the present invention to provide a so-called "manifold" spark plug setting by means of which two, four, six, eight or more plugs, which are arranged in a row, can be removed together from the cylinder block and can be put back in place without un-screwing and re-screwing each single plug, and by means of which all said plugs can be removed and replaced with less effort, skill and within a shorter period of time than has been required hitherto for the removal and replacement of one single plug.

Another object of the present invention is the provision of a device of the character described which requires but few and simple changes on the presently used cylinderheads, so that this device can be used not only on newly manufactured engines but can also be attached to any existing engines at a very low expense.

Yet still another object of the present invention is the provision of a device of the character described which is light in weight, which requires but little space, and which is simple in construction and inexpensive to manufacture, but which is sturdy and well adapted for the rough usage to which such devices are ordinarily subjected.

Further objects of the instant invention reside in any novel feature of construction or operation or novel combination of parts present in

the embodiment of the invention described and shown in the accompanying drawing whether within or without the scope of the appended claims and irrespective of other specific statements as to the scope of the invention contained herein.

In the drawing:

Figure 1 is a top plan view of a preferred embodiment of my invention as it appears when it is attached to a six-cylinder engine;

Figure 2 is a side elevation of the embodiment of Fig. 1;

Figure 3 is a sectional view on the line 3—3 of Fig. 2; and

Figure 4 is a side elevation of another preferred embodiment of my invention.

Similar numerals refer to similar parts throughout the several views.

Referring first to Figs. 1, 2 and 3, the numeral 1 denotes a cylinder head, which is indicated in dash-and-dotted lines in Fig. 1 and in full lines as vertical sectional view partially broken away in Fig. 2. The main part of my spark plug setting is a longitudinal bar 2, which 20 may be called a "manifold," of cast metal or the like, which consists of flat portions and of upwardly extending arch-shaped portions 3. A U-shaped slot 4 is vertically partially extended through each arch-shaped portion 3 and is adapted for receiving a threaded bolt 5 which has a nut and a washer at its upper portion. Each bolt 5 has a flattened lower portion through which extends a pivot pin 6 that is extended through lugs 7 which are welded upon or otherwise secured to or cast as a unit with the cylinder head 1. Each flat portion of the bar 2 has at its upper side a recess 8 and at its lower side lugs 9 which are in spaced relation to each other and adapted for being inserted into the countersunk portions of the spark plug holes which are in the cylinder head 1. A washer 10 is below each lug 9, and if the nuts on the bolts 5 are tightened the bar 2 and the lugs 9 will be pressed against the washers 10, so that no gas can escape through the countersunk portions of the sparkplug holes. I prefer to make the lugs 9 at both extremities of bar 2 a few thousandths of an inch higher than the other lugs so that the same pressure will be exerted upon all washers 10 even if the resiliency of the material of bar 2 should cause a slight bending of the same if the nuts on the bolts 5 are tightened. A threaded aperture extends through each lug 9 and through the adjoining flat portion of bar 55 2, and a spark plug 11 is screwed into each of

said threaded apertures in such a manner that its lower portion projects over the lower side of each lug 9 and protrudes into the cylinder in the usual manner, as may be seen in Figs. 2 and 3. Thus, the spark plugs 11 are screwed into bar 2, the recesses 8 being wide enough for inserting a socket wrench (not shown) around the plugs 11, so that each single plug has no longer to be screwed in the cylinder head.

The bolts 5 could be extended through simple vertical holes in bar 2. In this case, it would be necessary to unscrew the nuts entirely from the bolts 5. For facilitating the dismounting and re-mounting of the bar 2, I prefer to provide each arch-portion 3 with a reinforcement and with a slot 4, and to secure the bolts 5 hingedly or pivotally to the cylinderhead 1, as previously referred to. This arrangement allows a lateral swinging and disengagement of the bolts 5 from the slots 4 when the nuts have been loosened only. Thus an entire unscrewing of the nuts from the bolts 5 is not necessary, and the nuts remain always on the bolts 5 so that no nut can be lost during the manipulation of the device.

While the embodiment shown in Figs. 1 to 3 is satisfactory if pairs of spark plugs 11 are close together as shown and as is the case with many six and more cylinder engines, the arrangement shown in Fig. 4 may be preferred in the case of two or four cylinder engines or whenever there is a comparatively large distance between all plugs. According to this embodiment of the invention, the longitudinal bar is substituted by a member 2 which has flat extremities and an arch-shaped center portion 3, and each flat extremity has only one lug 9 and carries only one spark plug 11. The slot 4, bolt 5 and pin 6 are arranged in the same manner as explained in the description of Figs. 1 to 3, and lugs 21 are secured to or formed as a unit with the cylinder head 21.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

Having thus described my invention, what I claim and desire to secure by Letters Patent in the United States is:

1. A spark plug setting for multi-cylinder in-

ternal combustion engines comprising a manifold which has substantially flat portions and upwardly extending arch-shaped portions between each two of said flat portions, threaded bolts vertically extending through said arch-shaped portions and being secured to the cylinders of an internal combustion engine, and nuts screwed upon the upper portion of said bolts and adapted for pressing said manifold against said cylinders, said flat portions having at their lower side lugs which extend into the countersunk portions of the spark plug holes of the engine cylinders, and a bore being extended through each of said lugs and through the adjoining flat portion and being provided with a thread into which a spark plug is screwed in such a manner that the lower portion of each spark plug protrudes over the lower side of each lug, all substantially as set forth.

2. A spark plug setting for multi-cylinder internal combustion engines comprising threaded bolts hingedly secured to the cylinder head of the engine and having nuts screwed upon their upper portions, and a bar which consists of upwardly curved portions and of substantially flat portions having at their lower side lugs which extend into the countersunk portions of the spark plug holes of the engine cylinders, each of said upwardly curved portions having a U-shaped slot through which one of said bolts is extended, and a bore being extended through each of said lugs and through the adjoining flat portion and being provided with a thread into which a spark plug is screwed in such a manner that the lower portion of each spark plug protrudes over the lower side of each lug, all substantially as described.

3. A spark plug setting for multi-cylinder internal combustion engines comprising an arch-shaped member through whose center portion a horizontal slot is partially extended and whose lower end portions are provided with lugs adapted to be inserted into the countersunk portions of the spark plug holes of two adjoining cylinders of an internal combustion engine and with bores into each of which a spark plug is screwed in such a manner that the lower extremity of the plug protrudes over the lower side of the lug, a threaded bolt being pivotally secured to the cylinderhead of the engine and adapted to engage said slot, and a nut being screwed upon the upper portion of said bolt and being adapted for pressing said arch-shaped member against the cylinderhead, all substantially as described.

JOSEPH A. FINK.
